UNITED STATES PATENT OFFICE.

JOSEPH N. MCNEAL, OF BROCKWAY, MINNESOTA.

GOVERNOR.

SPECIFICATION forming part of Letters Patent No. 692,330, dated February 4, 1902.

Application filed November 2, 1901. Serial No. 80,905. (No model.)

To all whom it may concern:

Be it known that I, JOSEPH N. MCNEAL, a citizen of the United States, residing at Brockway, in the county of Stearns and State of Minnesota, have invented certain new and useful Improvements in Governors, of which the following is a specification, reference being had therein to the accompanying drawings.

10 My invention relates to speed-governors to regulate the motion of light machinery, and is especially well adapted for use in connection with geared wind-mills.

The object of this invention is to provide 15 a device of this class, of simple and inexpensive construction and automatic in its operation, which will transmit a steady motion to the driven shaft or mechanism used. I attain this object by the construction illustrated 20 in the accompanying drawings, in which—

Figure 1 represents a perspective view of the invention. Fig. 2 is a detail view showing the adjustable belt-tightener of the device.

In said drawings, A represents the driving shaft, which may be the vertical shaft of a wind-wheel, having vanes of suitable form. Said shaft carries a bevel gear-wheel *a*, secured thereto to give motion to any desired mechanism. At right angles to the shaft A 25 30 there is placed a shaft B, carrying on one end a bevel-gear *b*, which meshes with the gear *a*. Said shaft B is carried in bearings *c*, mounted upon a rectangular horizontal frame C, which may be secured to the frame 35 carrying the wind-wheel or to any other stationary support.

Upon the end of the shaft B opposite that occupied by the gears *b* is mounted a ball-governor D of ordinary construction, having 40 its outer boss *d* secured to the shaft B. Said boss has two arms *e* pivoted thereto, and balls *e*² are adjustably secured to said arms. To the arms *e* are pivoted, a short distance from the balls, arms *f*, which have their inner ends 45 pivoted to a sleeve F. The latter, adapted to slide upon the shaft B, has a groove in its periphery to receive loosely therein one end of a rod G, which end encircles said groove.

Mounted upon the frame C there is also a 50 shaft H, parallel with the shaft B, which carries upon one end a pulley *h*, from which a

steady motion can be transmitted to any suitable mechanism by a belt (not shown) adapted to be mounted upon said pulley. To transmit an adjustable motion from the shaft B to the shaft H, the shaft B carries a cone-pulley B² and the shaft H a cone-pulley H²; but their large ends are located adjacent to opposite sides of the frame C, and they are connected by an endless belt I, mounted thereon. To 55 automatically shift the position of the belt I upon the cones, the rod G, controlled by the ball-governor, is used. For this purpose said rod is made to pass between the cone-pulleys and through the loop of the belt, being retained 60 at a suitable height by the guide-eyes *k*, inserted in the top of the frame C. The rod G has mounted thereon two friction-rollers *g* to bear against the edges of the belt while shifting it. When the shaft B revolves faster than is desired, the too-rapid centrifugal motion of the 65 balls *e*² of the governor pulls the sleeve F away from the small end of the cone-pulley B² and the rod G pulls the belt I toward said small end, and consequently the large end of 70 the cone-pulley H², and reduces its speed. To counteract the action of the governor D and its sleeve F upon the rod G, there is secured thereto adjacent to one of the friction-rollers *g* one end of a chain or cord *m*, which 75 is made to pass over a guide-pulley *n*, mounted upon the frame C, the opposite end of the cord hanging down, and carries adjustable weights M upon said end of the cord.

To keep the belt I under constant tension, 80 an adjustable belt-tightener is used, which consists of a roller N, fully as long as the cone-pulleys. The ends of said roller are pivoted to arms *p*, which have one end pivoted to brackets *q*, pendent from the under side 85 of the frame C, so that the roller N bears normally upon the inner surface of the belt I. To render the pressure adjustable, weights *r* are adjustably mounted upon the arms *P*, as shown.

Having now fully described my invention, 90 I claim—

1. In a speed-regulator, the combination of a vertical shaft, carrying a bevel-gear, a horizontal shaft carrying a bevel-gear on one end, 95 a ball-governor and its sliding sleeve on the opposite end of said shaft, a rectangular

frame carrying said shaft, a cone-pulley upon said shaft, a second shaft having a belt-pulley on one end and carrying a cone-pulley, a belt uniting said cone-pulleys, a rod passing 5 through the loop of said belt and having one end connected with the sleeve of the ball-governor, friction-rollers upon said rod, and a weighted cord also connected with said rod, substantially as described.

- 10 2. In a speed-regulator the combination of two parallel shafts, cone-pulleys upon said shafts, a belt uniting said cone-pulleys, a ball-governor having its sliding sleeve mounted upon one of said shafts, a sliding rod having 15 one end connected with said sleeve and passing through the loop of the belt, two friction-rollers upon said rod, a rectangular frame carrying the cone-shafts, guide-eyes mounted upon said frame to guide the sliding rod and

a weighted cord connected with said rod, substantially as described.

3. In a speed-regulator, the combination of the frame C, two parallel shafts mounted thereon, cone-pulleys upon said shafts, a belt uniting said cone-pulleys, and an adjustable 25 belt-tightener consisting of a roller as long as said cone-pulleys, two pivoted arms supporting said roller and brackets secured to the frame C for the pivot, with weights adjustably mounted upon the pivoted arms, substantially as described.

In testimony whereof I affix my signature in presence of two witnesses.

JOSEPH N. MCNEAL.
